UNITED STATES PATENT OFFICE.

THOMAS S. LAMBERT, OF NEW YORK, N. Y.

BOX.

SPECIFICATION forming part of Letters Patent No. 234,297, dated November 9, 1880.

Application filed August 7, 1880. (Model.)

To all whom it may concern:

Be it known that I, THOMAS S. LAMBERT, a citizen of the United States, residing at New York, in the county of New York and State of New York, have invented new and useful Improvements in Boxes, of which the following is a specification.

The nature of this invention relates to a box adapted for the transportation of confections in the mails, and also for other purposes; and it has for its object to produce a box that shall be cheaply made, sufficiently strong to resist the pressure and concussions to which it may be subjected during transportation; of a light weight, in order to economize in postage; easily opened and safely closed, so that its contents may be readily inspected and the box then securely closed after such inspection; air-tight to preserve the confections in a soft, fresh state, and also to prevent any leakage of such portion of the confection as may become unduly softened or melted by exposure of the box to a high degree of temperature; of a shape which will not have sharp corners nor projections calculated to injure the accompanying mail-matter, and also of such construction that when opened the inclosed confections will be well displayed.

To such end my improvement consists in a box for transporting confections through the mails, the box-body made elliptic in cross-section, provided with closed convex or rounded ends, and formed with an opening extending nearly from end to end, in combination with a cover of greater area than the area of the opening which it closes, a flange more or less continuous arranged upon the under side of the cover and adapted to fit into the opening in the box, and an elastic band stretched over said flange and over the edge of the cover, and having a movable partition or partitions arranged within the box; also, lugs or catches projecting from the flange at one end of the box-cover and springs arranged at the other end of the cover so as to project into the box and act as spring-catches; also, in the box comprising a body made elliptic in cross-section, with closed ends and an opening, in combination with a cover provided with a continuous flange, devices for securing the cover in place, an elastic band stretched over the flange

and the edge of the cover, and a movable partition arranged within the body of the box, and provided with recess to receive the flange of the cover with the elastic band stretched over it, all as hereinafter more fully described.

In the accompanying drawings, Figure 1 represents, in perspective, a box for transporting confections in the mail, constructed in accordance with my improvement, the cover being in this instance removed in order to show more clearly the opening in the top of the box and also an adjustable partition in the box. Fig. 2 represents the cover in perspective, a portion of the elastic packing-band or gasket being broken away in order to show the flange and the lugs or catches. Fig. 3 is a longitudinal section taken through the box with its cover fitted thereto.

Like letters in the several figures indicate like parts.

A designates the body of the box, which is made of an elliptical form in cross-section. The ends B B of the box are made concavo-convex, and are secured air-tight to the body A, with their convex sides outward.

The oblong opening C extends nearly the entire length of the body A, narrow strips c c being left between the ends of the said opening and the ends of the box. These strips c c may be integral with the body A, or the said strips may be formed by securing separate pieces to the box.

The letter D designates the cover, which is made curved from side to side, so that when secured in place over the opening C its outer face will correspond to the general contour of the body of the box. This cover is made somewhat larger than the opening which it closes, so that its edges will fit against the body of the box, as indicated by the sectional view, Fig. 3.

Upon the inner or under side, d, of the cover is formed or secured a more or less continuous strip or flange, E, which should be about one-quarter of an inch in width and located at about one-quarter of an inch from the edge of the cover. This flange is formed so as to fit against the side and end edges of the opening C, whereby, when the cover is fitted to the box, the flange will extend through the said opening, while that portion d of the cover which is be-

between its edge and the flange will lie over the top face, *a c* of the body of the box, around the opening.

As a means for securing the cover to the box, 5 so as to guard against displacement when the box is transported, I provide the flange E with short lugs or catches F F, which may be formed either by slitting the flange and then bending down the material between such slits at right angles to the flange, or, if preferred, the lugs 10 may be formed separately from the flange and then secured thereto in any suitable way. A space about equal to the thickness of the material which composes the body A is left between 15 these lugs and the inner or under side of the cover, so that when the latter is fitted to the box these lugs will fit against the inner wall of the body A. These lugs are preferably arranged at one end of the cover, so as to 20 hold the same in position, while in order to secure the remaining end thereof I provide the cover with one or more springs, G, which, when the cover placed and pressed over the opening in the body of the box, pass with the 25 flange through said opening and secure the cover at that end, as represented in Fig. 3, which illustrates one of said springs. In order, however, to fit the cover to the box both 30 air and water tight, I stretch a band of rubber, H, over its edge, as shown in Fig. 2, the said band being of sufficient width to admit of its covering the flange E, the edge of the cover, and also the upper surface of the cover for a 35 distance about one-fourth of an inch from its edge.

When the cover provided with this elastic packing or gasket is fitted to the box, the said gasket will, by reason of its flexible and elastic properties, adapt itself to the conformation 40 of the joint between the body and the cover, and thus form an air-tight joint between the two.

The letter I designates a movable division or partition which is arranged within the 45 body of the box, in order to strengthen its walls and enable them to resist external pressure which might otherwise indent or crush the walls so as to injure the inclosed confection. This partition consists of an oval-shaped plate 50 made to fit against the interior surface of the body A, and it is formed with two recesses, *i i*, which receive the flange of the cover when the box is closed. More than one of these partitions may be employed, if desired.

55 The edges of the body of the box about its opening and the edges of the cover should usually be turned under, in order to stiffen the parts. In use the box should be also wrapped in strong paper, upon which directions will be

written, and after being thus wrapped it will 60 be properly corded. I also propose stretching an elastic band, H', around the box, so as to more securely hold the cover down, such band being preferably passed around the box and cover about the center thereof, or near 65 that end of the cover which is provided with the springs G.

I have described the box as especially adapted for the transportation of confections in the mail. It may, however, be used for other purposes.

Having thus described my invention, what I claim, and desire to secure by Letters Patent, is—

1. In a box for transporting confections through the mails, the box-body A, made elliptic in cross-section, provided with closed elliptical-formed ends, with an opening extending nearly from end to end, in combination with a cover of greater area than the area 75 of the opening which it closes, and a flange more or less continuous arranged upon the under side of the cover and adapted to fit into the opening of the box, and an elastic band stretched over said flange and over the edge 80 of the cover, all substantially as herein shown and described.

2. In a box for transporting confections through the mails, the combination, with the box-body A, provided with closed ends and with an opening, C, extending nearly from end to end of the cover D', a more or less continuous flange, E, secured to the under side of the cover, of the lugs F, projecting from the flange at one end of the cover, the springs G, 95 arranged at the other end of the cover, and the elastic band H, stretched over the edge of the box and likewise over the said flange, substantially as described.

3. The box comprising the body A, made 100 elliptic in cross-section, with closed rounded ends B and an opening, C, in combination with the cover D, provided with a flange, E, devices for securing the cover in place, an elastic band, H, stretched over the flange and the 105 edge of the cover, and a movable partition, I, arranged within the body of the box, and provided with recesses *i* to receive the said flange with the elastic band stretched over it, substantially as specified.

In testimony whereof I have hereunto set my hand in the presence of two subscribing witnesses.

THOMAS S. LAMBERT.
